UNITED STATES PATENT OFFICE.

JUNE A. PIERCE, OF CLAREMONT, NEW HAMPSHIRE, ASSIGNOR TO HIMSELF
AND JOHN T. EMERSON, OF SAME PLACE.

AUTOMATIC FELT OR WIRE GUIDE FOR PAPER-MAKING MACHINES.

SPECIFICATION forming part of Letters Patent No. 361,892, dated April 26, 1887.

Application filed September 23, 1886. Serial No. 214,331. (No model.)

To all whom it may concern:

Be it known that I, JUNE A. PIERCE, a citizen of the United States, residing at Claremont, in the county of Sullivan and State of New Hampshire, have invented certain new and useful Improvements in Automatic Felt or Wire Guides for Paper-Making Machines; and I do hereby declare the following to be a full, clear, and exact description of the invention, such as will enable others skilled in the art to which it appertains to make and use the same.

My invention relates to mechanism for automatically guiding and regulating the felt or wire-cloth of paper-making machines, but it is equally as well adapted for use in connection with any traveling belt or apron running over or under a roll or series of rolls, as the apron is the actuating agent by which the guide is brought into use.

Traveling belts and aprons, and particularly the felt or wire-cloth in a paper-machine, always have a tendency to stray laterally from their proper course, and the object of a guide is to check these movements and cause the apron to maintain a straight-forward uniform course. This is generally done by so arranging the guide that when the apron shifts sidewise it acts upon the guide and causes an axial change in the position of the conducting-roll which effects the desired results. I propose to guide the felt or wire-cloth in the same general way, but with a more direct and quicker action of the parts; and to this end the invention consists in the construction and arrangement of the mechanism, all as will be more fully hereinafter described and claimed.

For the better understanding of my invention attention is invited to the accompanying drawings, in which similar letters denote corresponding parts in each figure, and in which—

Figure 1 is a perspective view of the conducting-roll, the guide, and its co-operative mechanism; Fig. 2, an end elevation of the same; Fig. 3, a plan view; Fig. 4, a side elevation, partly in section; and Fig. 5, a vertical section of the sliding or reciprocating bearing for the conducting-roll.

A denotes the conducting-roll, over which the felt or wire-cloth A' passes to the return-

roll A². This conducting-roll is supported at one end in a fixed standard, A³, bolted to the bed-plate C, and at the other end is supported in a sliding or reciprocating bearing, B, arranged upon a standard, B', bolted to the bed-plate C'. This standard B' is arranged at a right angle to the axis of the conducting-roll and has two longitudinal side flanges, b b, which guide the bearing B in its movement back and forth upon said standard. This bearing is guided above by a cap-plate, B², which is about as long as the standard B', and is secured thereto by bolts b' b', which pass through respective tubes b² b² at each end. These tubes hold the cap-plate above the standard far enough to allow free movement of the sliding bearing between said cap-plate B² and standard B'.

The sliding bearing B is preferably a casting consisting of a square block, a, and an adjoining extension, a'. (Fully shown in the detail, Fig. 5.) Part a is that portion which moves upon the standard B' and has a central opening to receive the shaft C² of the conducting-roll A. The shaft C² at this end carries a spiral driving-gear, C³, which plays within a socket, c, of the extension a' of the sliding bearing B, and meshes above with another spiral gear, D', arranged at a right angle thereto between two ears, d d, of the extension a' of the sliding bearing B. This gear D' has tubular hub-bearings in said ears d d and is adapted to work back and forth with the sliding bearing B by being splined to a feed-shaft, D, which passes through it and its hubs and has bearing at one end in an extension of the standard B'.

E is a right or left hand screw-shaft arranged parallel with the feed-shaft D below and passing through a properly screw-threaded ear, e, of the extension a' of the sliding bearing B, and also through a bushing, e', in that portion of the standard B' which supports one end of the feed-shaft D.

The bushing e' is secured by a set-screw, e², and on the end of this screw-shaft E, outside of and next to its bearing in the extension of standard B', is splined a toothed wheel, F, by which the said shaft E is operated to move the sliding bearing B to shift one end of the conducting-roll A. On the extreme end of this

screw-shaft E, and next to the hub of the toothed wheel F, is fitted a flanged bushing, f, which clamps the toothed wheel by means of a nut, f', screwed on this end of the screw-shaft 5 E. On this bushing f is loosely mounted a rocker-shield, G, the upper end of which is curved and flanged so as to cover about one-fourth the circumference of the toothed wheel F, for a purpose hereinafter understood.

10 On the end of the feed-shaft D, outside of and next to its bearing in the standard B', is secured a disk, g, having near its periphery on the outside a pin or stud, g', upon which are hung two oppositely-disposed pawls, H H.

15 These pawls, which are held in place by a nut, g'', are united by a spiral spring, h, and are so arranged as to ordinarily rest upon the flange of the rocker-shield G out of engagement with the toothed wheel F. This is the position of 20 the pawls when the felt or wire-cloth is pursuing its proper course over the conducting-roll.

To give effective action to either of the pawls—that is, to bring them into engagement 25 with the toothed wheel F, so as to rotate the screw-shaft E, and in turn move the sliding bearing B to shift one end of the conducting-roll—it is necessary to tilt or depress that end of the rocker-shield upon which rests the pawl 30 to be used. Either of these movements is effected by tilting the shield, which is actuated by a lever, I, which is made fast at its center to a rock-shaft, J, presently to be described.

The lower arm, k, of this lever extends down 35 to the rocker-shield G, and is connected thereto by a pin or stud, l, which works in a slot, l', in the lower end of said arm. The upper arm, k', of this lever is formed into a segment and supports one end of the shipper-rod K, which 40 carries the two adjustable guide-plates L L and which extends transversely across the traveling felt or wire-cloth. The opposite end of this shipper-rod is likewise supported upon a similar-shaped standard, M, having lower pivot-bearings between two ears, m m, of a bracket, 45 N, bolted to the bed-plate C. Over each end of the shipper-rod is clamped an arm, O, by means of a set-screw, n, and these arms are held in connection with the lever I and standard M by a pin, o, on the top of each. The guide-plates L L are likewise clamped to the shipper-rod by means of set-screws n'. The rock-shaft J, to which the lever I is secured, 50 is arranged parallel with the feed-shaft D, and back of the same in substantially the same horizontal plane, and is journaled at each end in bearings p p, secured to the cap-plate B² of the standard B'. This rock-shaft has two projecting ears, r r', the former being above and 55 the latter being below its horizontal center. The object of these ears and their arrangement is that when the sliding bearing B is moved forward or backward the lug s on its extension a' will engage with the ears r and r' and tilt 60 the shaft J either up or down, as the case may be. For instance, supposing the sliding bear-

ing B to be moving toward the end bearings of the several shafts, then in passing the ear r its lug s would make contact with said ear from below and tilt the shaft J upward, and, 70 on the contrary, if moving in the opposite direction, the lug s would make contact with ear r' from above and tilt the shaft J downward, and hence both the lever I and the rocker-shield G would be tilted, so that one of the 75 pawls H would be disengaged from the toothed wheel F, while the other one would be made to engage therewith, thus either time reversing the screw-shaft and the sliding bearing.

As the conducting-roll revolves motion is 80 imparted to the feed-shaft and to the pawls which are hung thereon, and, if the felt or wire-cloth is moving forward and uniformly, with its side edges in straight lines of direction, the said pawls will work eccentrically without 85 engaging with the teeth of the wheel F; but as soon as it begins to shift sidewise it will crowd itself against one of the guide-plates L, which will shift the shipper-rod K, and in turn tilt the lever I and the rocker-shield G. By tilting this shield one of the pawls H will be thrown into engagement with the toothed wheel F, which will actuate the intermediate connections so as to shift the one end of the conducting-roll. By thus changing the axial 95 position of the conducting-roll it tends to give the felt or wire-cloth lateral divergence in an opposite direction, whereby it may be shifted and returned to its proper path of travel.

By means of the rock-shaft the movement of 100 the sliding bearing is reversed in either direction, as the case may be.

Having thus described my invention, what I claim, and desire to secure by Letters Patent, 105 is—

1. In a felt or wire guide for paper-making machines, a shipper-rod provided with two adjustable guide-plates and with two adjustable supporting-arms connected to tilting levers, substantially as described.

2. In a felt or wire guide for paper-making machines, the combination of a conducting-roll having a fixed bearing and a movable bearing, and a shipper-rod provided with two guide-plates and connected at one end to a 115 tilting standard and at the other end to a tilting lever connected with the mechanism for shifting the movable bearing of the roll, substantially as described.

3. In a felt or wire guide for paper-making machines, the combination of a conducting-roll having a fixed and a movable bearing, a feed-shaft and a screw-shaft passing through said movable bearing at right angles to the roll, intermediate spiral engaging gears on the 125 feed-shaft and the shaft of the conducting-roll, and connections between the corresponding ends of the feed-shaft and screw-shaft for rotating the latter, substantially as and for the purposes set forth.

4. In a felt or wire guide for paper-making machines, the combination of a conducting-

roll having a fixed and a movable bearing, a feed-shaft and a screw-shaft passing through said movable bearings at right angles to the conducting-roll, a gear splined to said feed-shaft and having tubular hub-bearings in said movable bearing, an engaging driving-gear on one end of the roll-shaft, a pair of spring-connected pawls hung upon one end of the feed-shaft, a toothed wheel and a rocker-shield 5 mounted upon the corresponding end of the screw-shaft, and a tilting lever pivoted to said rocker-shield and connected with one end of the shipper-rod, substantially as and for the purposes set forth.

15 5. In a felt or wire guide for paper-making machines, the combination of a conducting-roll having a fixed bearing and a movable bearing provided with a stud, a rock-shaft provided with two ears above and below its 20 horizontal center, and a tilting lever hung upon one end of said rock-shaft and connected with one end of the shipper-rod and with the

mechanism for shifting the movable bearing of the conducting-roll, substantially as described.

6. In a felt or wire-cloth guide for paper-making machines, the combination of a pair of guides, a shipper-rod, a tilting standard, a tilting lever hung at its center upon a rock-shaft provided with two ears, and intermediate feed and screw shafts passing through a 25 movable bearing provided with a stud and carrying on their corresponding ends, respectively, a pair of oppositely-disposed spring-united pawls and a toothed wheel and flanged rocker-shield, all combined and operating by 30 means of gearing intermediate the conducting-roll and feed-shaft, substantially as described.

In testimony whereof I affix my signature in presence of two witnesses.

JUNE A. PIERCE.
